CONDENSER

Alfred R. Muirhead, Columbus, Ga., assignor to
Lummus Cotton Gin Company, a corporation
of Georgia

Application June 30, 1943, Serial No. 492,819

12 Claims. (Cl. 19—156)

This invention relates to condensers such as are employed in separating air borne fibrous materials from their accompanying air currents and has for an object the provision of apparatus of the character designated which shall be simple and sturdy of design and which shall embody improved means for collecting and discharging material from the apparatus.

A further object of my invention is to provide a condenser of the type comprising a rotary 10 foraminous drum, means to create a partial vacuum within the drum, and means to limit the area of the drum through which air is drawn during its rotation, in which an endless apron cooperates with the drum over a part of its active area to hold the material collected on the drum surface until it passes to an inactive part of the cycle of operation and is discharged from the machine.

A still further object of my invention is to provide a suction condenser including a rotary foraminous drum in which the drum is partially enclosed within a casing and the area of the drum subject to suction is limited to a part of its cycle of operation, and in which improved 25 sealing means are provided to prevent leakage of air into the casing or the drum from the outside.

Another object of my invention is to provide a suction condenser for separating air borne fibrous material from its accompanying air current which shall include a moving apron to aid in collecting and discharging material from the condenser drum, and in which improved means are provided for driving the drum and the apron to cause them to travel in unison.

In the operation of suction condensers as heretofore known to me difficulties have been encountered due to the breaking of the partial vacuum within the condenser drum when large lumps or masses of material become collected on the drum surface. It has been the usual practice to employ a roll, or hinged back, separating the space between the active portion of the drum surface and the inactive portion thereof, and these rollers or backs, being rigid members, are pushed outwardly by irregular masses of material when such are encountered, thus leaving unsealed spaces between the roller and the drum surface through which air may leak to the inside of the drum. When this occurs, the vacuum within the drum is broken, the apparatus does not function properly and increased power is required to keep up the flow of air necessary to maintain the material being collected in transit.

These and other difficulties are overcome by means of my invention which, briefly, is a condenser of the type embodying a rotary foraminous drum, with means inside the drum to separate it into active and inactive zones for the purpose of collecting and discharging materials therefrom. A casing partially encircles the active zone and, in accordance with my invention, I provide an apron or belt moving with the surface of the drum and covering the remainder of the active surface thereof so as to aid in forming the bat of material on the drum and in discharging it therefrom. The moving apron effectively seals the drum over the area it contacts and prevents the leakage of air thereinto along the sides and at the point of material discharge, and thus insures operation of the condenser at a uniform, partial vacuum. Other features of my invention reside in improved means for sealing off the active zone of the condenser against the ingress of air from the outside, in the mounting and arrangement of the moving apron, and in the improved driving means for the condenser and for the apron.

Apparatus embodying features of my invention is illustrated in the accompanying drawings forming a part of this application, in which

Fig. 1 is a longitudinal sectional view of the apparatus taken along the line I—I of Fig. 3;

Fig. 2 is an end elevational view with certain parts broken away, and showing one form of drive;

Fig. 3 is a transverse sectional view taken along the line III—III of Fig. 1;

Fig. 4 is a fragmentary sectional view drawn to an enlarged scale illustrating the manner of sealing off the inactive portion of the condenser drum;

Fig. 5 is a fragmentary sectional view drawn to a larger scale and taken along the line V—V of Fig. 2;

Fig. 6 is a detail view of a casing head;

Fig. 7 is a fragmentary edge view of the casing head and guides; and

Fig. 8 is a fragmentary end view showing a modified form of drive.

Referring to the drawings for a better understanding of my invention, I show a main frame comprising horizontally extending end frame members 10, 11, and 12 extending across the apparatus at top, center, and bottom respectively. The end frame members are joined to vertically extending frame members 13 and 14, and the latter are joined by horizontally extending side frame members 16, 17, 18, 19, 20, 21, and 22.

Rigidly mounted between the end frame members 11 is a horizontally extending shaft 23, the shaft being secured to the members 11 by suitable securing means such as bolts 24. Mounted for free rotation on the shaft 23 is a material collecting drum comprising circular channel-like heads 26 and 27 having spokes 28 and 29 connecting them to hubs 31 and 32 which are journalled on the shaft 23, the hubs 31 and 32 being free to rotate on the shaft. Mounted on the heads 26 and 27 is the usual foraminous cover 33. The outer flanges of the heads 26 and 27 are provided with sprocket teeth 34 for driving the drum in a manner to be described later. The drum is closed at one end by means of a cover plate 36 fitting over the inner flange of the head 26, while the other end is connected to the usual suction conduit 37. The suction conduit 37 is flared at 38 to connect to a stationary ring 39 which is secured in any suitable manner to the cross frame member 11. A circular sealing strip 41 is secured to the inner flange of the head 27 and overlaps the ring 39 to prevent leakage of air from the outside into the suction connection, which would tend to prevent the formation of the partial vacuum within the drum, necessary for the operation of the condenser. The suction pipe is flared to compensate for the obstruction to the flow of air afforded by the cross member 11 and spokes 29 at the end of the drum.

Mounted within the lower part of the drum is an imperforate sheet metal housing 42 which is supported at its ends by semi-circular rims 43. The rims 43 are provided with spokes 44 and 46 connected to central hubs 47 and 48 which are secured to the shaft 23 by any suitable means such as set screws 49, so that the housing 42 remains stationary within the drum as the latter rotates about the shaft 23. The spokes 44 and 46 are connected together by longitudinally extending sheet metal members 51 and 52 which extend from end to end of the drum. Mounted on the members 51 and 52 and extending downwardly to contact the inner surface of the perforate cover 33 are flexible sealing strips 53 and 54. See Fig. 4. To prevent leakage of air around the ends of the housing 42, I provide flashing strips 56 and 57 which are joined to the rims 43 and contact the outer surface of the heads 26 and 27 just beneath the perforate cover 33. The ingress of air due to suction through the conduit 37 is accordingly limited to the upper part of the drum.

Suitably supported in bearings 58 and 59 mounted on the upper frame members 10 is an upper sprocket shaft 61. A similar lower sprocket shaft 62 is mounted in bearings 63 and 64, which are in turn mounted on the lower frame members 12. Mounted on the ends of the upper sprocket shaft 61 are sprocket wheels 66 and 67 and between the sprocket wheels 66 and 67 is a roller 68, having a diameter equal to the pitch diameter of the sprockets 66 and 67, and extending the full distance between said sprockets. Similarly, the lower sprocket shaft 62 has mounted on its ends sprocket wheels 69 and 71 and between them a roller 72, similar to the roller 68. A sprocket chain 73 connects the sprocket wheels 66 and 69 and a similar sprocket chain 74 connects the sprocket wheels 67 and 71. On the outer sides of each of the sprocket chains 73 and 74 are clips 76 to hold the chains against lateral displacement. See Fig. 5. The chains 73 and 74 engage the teeth 34 on the drum heads as shown and rotate the drum.

Mounted on the rollers 68 and 72 between the

sprockets 73 and 74 is an endless substantially imperforate apron or belt 77 which is of ample dimensions to extend from the sprocket 66 to the sprocket 67 and also to flex responsive to suction 5 within the drum to accommodate material collected on the drum surface. The apron 77 is secured to the chains 73 and 74 by means of clips 78 secured to the sides of the links of the chains as shown particularly in Fig. 5. The apron 77, 10 being loosely mounted on the drum, bags under the influence of a partial vacuum within the drum, and assumes a position such as shown in Figs. 3 and 5 to cover the drum surface from the point X to the point Y, thus covering a portion of the active surface of the drum and a part of the inactive surface, defined by the housing 42, so that material collected on the active portion of the drum surface is held against the drum until it reaches the inactive zone and is then freely discharged therefrom. The apron and drum, being driven by the chains 73 and 74, travel at the same speed.

Enclosing the remainder of the active surface of the drum is a casing having arcuate heads 79 and 81 secured by any suitable means, not shown, to the upper frame members 17 and longitudinal members 19 and 20. A cover 82 extends over the end frame members 79 and 81 and terminates at the rear of the apparatus adjacent the apron 77. The lower forward ends of the members 79 and 81 are joined by a plate 83 extending the length of the apparatus and define, with the cover 82, an inlet opening 84 for a conduit 86 carrying air borne fibrous material to be separated. A flexible sealing strip 87 is joined to the rear edge of the plate 83 and bears against the outer surface of the cover 33 to prevent the leakage of air into the casing. See Fig. 4. The heads 79 and 81 are sealed against leakage by means of angular 30 sealing strips 88 and 89 carried by the heads 79 and 81, respectively, and bearing against the outer surface of the cover 33 where it joins the heads 26 and 27.

The rear of the casing terminates in a tubular 45 guide rail 91 which is joined to the heads 79 and 81 as shown in Fig. 7, and against which the apron 77 is adapted to bear, in operation, to seal against leakage of air into the casing between the apron and the casing.

The casing heads 79 and 81 are each cut off at the rear along a line 92 which is tangent to the peripheries of the cover 33 and the sprocket wheels 66 and 67. At the rear of the casing the heads 79 and 81 are provided with bosses 95 on which are mounted guide bars 96 (see Figs. 5, 6, and 7), which are joined to the bosses by means of screws 97 or any other suitable fastening means. The guide bars 96 extend downwardly across the heads along the line 92 and are engaged by the extension clips 76 on the outside of the chains 73 and 74, already described, to hold the chains in alignment against the inward pull of the apron 77 due to the suction acting inwardly of the drum. As shown in Fig. 5 of the drawings, the belt or apron 77 is carried by the sprocket chains 73 and 74 along the outer ends of the casing head and bears tightly against the end flanges 75 on the casing heads so as to seal off that portion of the casing from the ingress of air between the belt or apron and the casing heads. The suction effect on the belt or apron 77 is such as to draw it into tight engagement with the outer surfaces of the casing heads.

The apparatus may be driven in several ways, 75 two being shown in Figs. 2, 3, and 8. Referring

first to Fig. 2, I show a shaft 98 extending longitudinally beneath the drum and mounted in suitable bearings 99, carried by the lower cross frame members 12. Mounted on the shaft 98 is a pulley 101 carrying a cross belt 108 which extends rearwardly and passes over a pulley 109 mounted on the shaft 62.

Also mounted on the shaft 98 is a wiper cylinder 105 carrying a plurality of flexible wiping blades 107 which, on rotation of the shaft, contact the surface of the drum cover 33 and wipe off any material which might be clinging to the surface, the wiper blades extending the full length of the drum.

In Fig. 8 I show a modified form of drive viewed from the end of the apparatus opposite that shown in Fig. 2. In accordance with this modification, I mount a sprocket 110 on the shaft 98' and an idler sprocket 111 on the vertical frame member 13'. A third sprocket 112 is mounted on the shaft 62'. A chain 113 connects the sprockets 110 and 111 and also engages the teeth on the sprocket 112 to drive the shaft 62. The sprocket 111 is mounted in adjustable bearings 114 whereby the tension on the chain 113 may be maintained.

The shaft 98 is driven by a pulley 115 in a counterclockwise direction as viewed in Figs. 2 and 3 to effect rotation of the drum in the same direction so that material entering the casing from the inlet 36 is drawn on to the surface of the drum in the active zone defined by the upper forward edge of the housing 42 and forms a bat on the surface of the drum. As the drum rotates, and the bat reaches the apron 17, the latter covers the drum and the bat and prevents further ingress of air through the bat, or around any irregular mass of material on the drum into the interior of the drum. The loose apron or belt is held in tight engagement with the bat until it passes the upper rear edge of the housing 42 when it is no longer acted upon by the partial vacuum within the drum and it falls by gravity from the surface of the drum. It will be seen that the apron, being loose and yielding, will close down over the drum around any irregular shaped mass of material and preserve the partial vacuum within the drum. I have found this to be true no matter how bulky or irregular in size the mass of material may be. Furthermore, an irregular mass of material passing out at one side of the apron does not allow any air to enter the casing at either side of the mass due to the loose bagging effect of the apron in bearing against the material. Also, as already described, the belt or apron 17 effectively seals the casing against the ingress of air across the ends of the casing heads 79 and 81.

From the foregoing it will be apparent that I have devised an improved condenser which is simple and sturdy of design and operation, and which includes improved means for collecting and discharging fibrous material from the surface of the drum.

While I have shown my invention in but two forms, it will be obvious to those skilled in the art that it is not so limited, but is susceptible of various changes and modifications, without departing from the spirit thereof, and I desire, therefore, that only such limitations shall be placed thereupon as are specifically set forth in the appended claims.

What I claim is:

1. In a condenser, a rotary foraminous drum, a casing partially surrounding the drum and

having an inlet opening along one side for air borne material, suction means connected with the interior of the drum through one end thereof, means in the drum to exclude air from passing through a part of the surface of the drum outside the casing, and a substantially imperforate apron moving with the surface of the drum to exclude air from the remainder of the drum surface outside the casing.

2. In a condenser, including a horizontally disposed rotary foraminous drum and suction means connected with an end of the drum to draw air through the drum surface, means within the drum for dividing it into active and inactive

15 portions, a casing partially surrounding the active portion of the drum and having an inlet opening along one side for air borne material, and a substantially imperforate moving belt covering the remainder of the active portion of the drum surface to exclude air from that portion of the drum and discharge material collected on the drum surface.

20 3. In a condenser, a rotary foraminous drum, suction means for creating a flow of air inwardly through the drum surface, means limiting the flow of air through the drum surface to a part of its cycle of rotation, a casing over a part of the drum through which air is permitted to flow, and having an inlet opening along one side thereof for air borne material to be separated, and a substantially imperforate belt outside the drum covering the remainder of the active drum surface outside the casing to impede the flow of air therethrough and discharge material collected on the drum surface.

25 4. In a condenser, a rotary foraminous drum, suction means for creating a flow of air inwardly through the drum surface, stationary means within the drum for closing off the flow of air through a part of its surface and dividing the area circumscribed by the drum into an active zone and an inactive zone, a casing over a part of the active zone, and a substantially imperforate belt outside the drum disposed to travel with the drum outside the casing through the remainder of the active zone and to hold material collected on the drum surface in contact therewith until it reaches the inactive zone.

30 5. In a condenser, a horizontally disposed rotary foraminous drum, suction means for creating a flow of air inwardly through the drum surface, a casing over the upper portion of the drum and having an inlet along one side for air borne material to be separated, a stationary closure within the drum for closing off the flow of air through the lower portion of the drum and dividing the area circumscribed by the drum into active and inactive zones, and a substantially imperforate belt moving with the downgoing side of the drum 35 surface through a part of the active zone and disposed to cover and hold material in place on the drum surface until it reaches the inactive zone.

40 6. In a condenser for air borne fibrous material, a rotary foraminous drum, suction means for creating a partial vacuum within the drum, a stationary partition within the drum dividing the area defined by the drum surface into active and inactive zones, a casing for the drum extending over the major portion of the active zone, a loose belt covering the remainder of the active zone on the discharge side of the drum and overlapping one end of the casing to seal it against ingress of air, and a sprocket chain to which the belt is attached and adapted to drive the belt and the 45 drum together.

7. In a condenser for air borne fibrous material, a rotary foraminous drum, suction means for creating a partial vacuum within the drum, a stationary partition within the drum dividing the area defined by the drum surface into active and inactive zones, a casing for the drum extending over the major portion of the active zone, a sprocket chain at each end of the drum and adapted to rotate the drum, a belt loosely spanning the space between the sprocket chains and bearing against the drum through the remainder of the active zone, and means at one end of the casing coacting with the belt to seal the casing against the ingress of air.

8. In a condenser for air borne fibrous material, a rotary foraminous drum, suction means for creating a partial vacuum within the drum, a stationary means within the drum dividing the area defined by the drum surface into active and inactive zones, a casing for the drum extending over the major portion of the active zone, a sprocket chain at each end of the drum and adapted to rotate the drum, a belt loosely spanning the space between the sprocket chains and bearing against the drum through the remainder of the active zone, means on the end of the casing coacting with the belt to prevent the ingress of air into the casing past the belt, and guide means carried by the casing for holding the sprocket chains against lateral displacement.

9. In a suction condenser for air borne fibrous material, the combination of a foraminous drum, means to rotate the drum, means for subjecting the drum to suction during a period of its cycle of rotation, means for closing off the action of suction over a section of the drum surface during another period of its cycle of rotation, and a sub-

stantially imperforate apron disposed to move with the surface of the drum and to be drawn toward the drum by suction during the latter part of the suction period.

5 10. In a condenser for air borne fibrous material, a rotary foraminous drum, suction means for creating a partial vacuum within the drum, a stationary means within the drum dividing the area defined by the drum surface into active and inactive zones, a casing for the drum extending over the major portion of the active zone, a sprocket chain at each end of the drum and adapted to rotate the drum, a substantially impervious belt loosely spanning the space between the 15 sprocket chains and bearing against the sides of the casing and adapted to bag inwardly responsive to suction within the drum, a guide rail extending across the rear of the casing and adapted to have sealing engagement with the belt when 20 the condenser is in operation, means to secure the sides of the belt to the chains, and means to hold the chains against displacement responsive to lateral pull by the belt.

11. Apparatus as set forth in claim 10 in which 25 sealing strips coact between the sides of the casing and the drum to prevent ingress of air from the outside into the casing.

12. Apparatus as set forth in claim 10 in which the means within the drum dividing the area defined by the drum surface into active and inactive zones comprises a semicylindrical sheet metal housing mounted within the drum, means for holding the housing against rotation, and sealing means along the edges of the housing and at the 35 ends to preclude ingress of air into the drum around the housing.

ALFRED R. MUIRHEAD.
